UNITED STATES PATENT OFFICE.

NILS LEONARD ÅKERBLOM, OF STOCKHOLM, SWEDEN.

METHOD OF RECOVERING CYMENE OBTAINED IN SULFITE-CELLULOSE PROCESS.

1,333,694.

Specification of Letters Patent. Patented Mar. 16, 1920.

Application filed February 11, 1918. Serial No. 216,540.

To all whom it may concern:

Be it known that I, NILS LEONARD ÅKERBLOM, a subject of the King of Sweden, residing at 7 Vasagatan, Stockholm, Sweden, have invented certain new and useful Improvements in Methods of Recovering Cymene Obtained in Sulfite, Cellulose Processes, of which the following is a specification.

10 My present invention refers to a method of recovering an oily product obtained in the sulfite cellulose factories and containing cymene and other hydrocarbons, resins and other constituents. This oily product is in the following description called cymene after its most valuable constituent.

15 In boiling sulfite cellulose, the gases escaping from the boilers during the boiling operation or after the same are led into receptacles containing "acid" prepared for use in a subsequent boiling operation in order to recover sulfurous acid and other gases. These gases also contain the cymene which is, thus, accumulated in the receptacle.

20 The present invention now has for its object the recovering of the cymene which is lighter than the acid and thus rises to the surface and floats as a thin layer on the same. With this object in view the principal 25 feature of my invention consists in raising from time to time the surface of the liquid contained in the receptacle, increasing the thickness of said layer by forcing it into a narrow portion of the receptacle, and leading off the cymene from said narrow portion through suitable outlets. The raising of the surface of the liquid is executed by introducing into the receptacle acid or other liquid which has a higher specific gravity 30 than cymene. This separating of the cymene may be executed in a second receptacle connected with that receptacle (here referred to as main receptacle) into which the gases are led from the boiler, and into 35 which second receptacle is led a small quantity of acid on which floats the layer of cymene which has been left in the main receptacle when emptying the same through an outlet at its lower end. The separating 40 of the cymene according to this invention may also be performed in the main receptacle, provided that this one has a tapered upper portion or is provided with a narrow neck.

45 55 Another feature of my invention consists in performing the raising of the surface of

the liquid stepwise, *i. e.* in such a manner that first a rough regulating is executed by introducing acid or other heavier liquid into the receptacle until the surface of the liquid has been raised to or nearly to the tapered portion or neck, and then executing a fine regulating of the raising of the surface in acid portion or neck by introducing acid, water or other heavy liquid through a more narrow conduit into the upper or lower portion of the receptacle.

50 Other features of my invention will be clear from the following description of the method, reference being had to the accompanying drawings schematically illustrating two different forms of apparatus.

55 Figure 1 shows a system of apparatus to be used in executing the invention. Fig. 2 shows another form of apparatus.

60 In Fig. 1 the main receptacle A receives through the conduit B the gases from the boiler, the surface of the liquid on which floats the cymene being then at I. Thereafter the liquid is taken out from the main receptacle through the conduits N and O, the valve M on the conduit N and valve S on conduit O being then open and the valve P closed. When the surface of the liquid has been lowered to the level II, valve S is closed 65 and the valve P opened, so that the remaining acid on which the layer of cymene is floating is introduced into the receptacle Q, where the liquid is assumed to rise to the level I. After the valve P has been closed, 70 the surface of the liquid is raised to level 2 (rough regulating) by introducing acid or other heavy liquid through the conduit C, the valve G provided in the same being then open. Then the valve G is closed and the valve H on the narrower tube D is opened, 75 so that acid from C is introduced into the upper narrow portion of the second receptacle Q. Instead of acid from C water or other liquid may be introduced into the tube 80 D from a conduit F provided with a valve I. By this means a very fine regulating of the raising of the layer of cymene within the upper narrow portion of the receptacle is rendered possible until the cymene flows off 85 through the conduit L from which it is recovered practically free from acid.

90 According to Fig. 2 the cymene is separated from the acid within the main receptacle A receiving gases from the boiler through conduit B. The main receptacle is provided with a neck E in which the sepa-

rating take place. The surface of the liquid originally stands at 1 and is then raised to 2 by introducing acid from conduit C into the receptacle (rough regulating). Then 5 acid from C or water from F is introduced into the neck E where the previously thin layer of cymene becomes thicker and now rises in the neck and flows off through conduit L until the acid has been raised nearly 10 to the level of the outlet, at which moment the valve T located in the conduit L is closed.

The difficulty of separating the cymene from the acid is due to the fact that the 15 cymene is present in minute quantities and, consequently, that the layer of the same is very thin. Heretofore one has therefore from time to time tapped off great quantities of acid together with cymene into large 20 receptacles and accumulated them there until a sufficiently thick layer of cymene for being skimmed off has been formed. Even after the skimming off of the cymene the latter has contained great quantities of acid 25 which it has been necessary to separate in some way or other. The present invention renders it possible by simple means to separate the last drops of cymene practically free from acid. The cymene obtained in 30 this way is, consequently, immediately ready for use. The minute quantities of acid which may be mingled with the same may readily be removed by adding a neutralizing agent, such as lime stone, chalk or 35 lime.

The above method may of course also be used for separating under analogous conditions small quantities of any light liquid from a heavier liquid.

40 Having now described my invention, what I claim and desire to secure by Letters Patent is:

1. The herein described method of re-

covering cymene obtained in the sulfite cellulose process, consisting in leading gases 45 from a cellulose boiler into a receptacle containing acid for a subsequent boiling operation, tapping off the greatest part of said acid from the lower end of the receptacle, leading off the remaining acid together with 50 the cymene floating on the same to a second receptacle, raising the surface of the liquid in said second receptacle by introducing into the same a heavier liquid than cymene, increasing the thickness of the 55 layer of cymene by forcing it into a narrow portion of the receptacle and leading off said layer of cymene, substantially as described.

2. The herein described method of recovering cymene obtained in the sulfite cellulose process, consisting in leading the gases from a cellulose boiler into a receptacle containing acid for a subsequent boiling operation, tapping off the greatest part 65 of said acid from the lower end of said receptacle, leading off the remaining acid together with the cymene floating on the same to a second receptacle, raising the surface of the liquid in said receptacle by introducing a heavier liquid than cymene through a conduit, increasing the thickness of the cymene layer by forcing it into a narrow portion of the receptacle by means of a heavier liquid than cymene introduced 70 through a narrower conduit than the first mentioned one and leading off the cymene from the upper part of said narrow portion, substantially as described and for the purpose set forth.

80 In testimony whereof I have affixed my signature in presence of two witnesses.

NILS LEONARD ÅKERBLOM.

Witnesses:

AXEL EHRNER,

JACOB BAGGE.
